UNITED STATES PATENT OFFICE.

JOHN SALTAR, JR., OF PHILADELPHIA, PENNSYLVANIA.

GAS-RETORT CHARGER.

SPECIFICATION forming part of Letters Patent No. 756,059, dated March 29, 1904.

Application filed January 11, 1904. Serial No. 188,472. (No model.)

To all whom it may concern:

Be it known that I, JOHN SALTAR, Jr., of Philadelphia, in the State of Pennsylvania, have invented certain new and useful Improvements in Gas-Retort Chargers, whereof the following is a specification, reference being had to the accompanying drawings.

My improvements relate to apparatus for feeding fuel to gas-generators, and comprising a rotative or oscillative vessel having an opening in the top into which a charge of fuel is primarily received and which is quickly semirotated with respect to the retort or producer casing in order to empty the fuel charge into the latter, after which the vessel is as quickly reversed, mouth upward, ready to receive another charge.

As hereinafter described, my invention comprises a rotative or oscillative fuel vessel fitted to a seat in the mouth of such a casing or retort, open on one side to receive the charge, provided with means whereby it may be rocked to deliver the charge to the retort, and also provided with means to press the vessel upon said seat to securely seal the retort during the intervals between successive charging operations.

In the form of my invention hereinafter described the trunnions upon which the receiving vessel is arranged to be rocked are mounted in bearings provided with means to adjustably increase and diminish the pressure of said vessel upon its seat in the mouth of the retort and also to vary the position of said vessel to accurately fit said seat and compensate for wear of the parts.

My invention comprehends the various novel features of construction and arrangement hereinafter more definitely specified and claimed.

In the drawings, Figure I is a side view of the upper portion of a gas-producer casing or retort, showing a convenient embodiment of my invention. Fig. II is a sectional view of the device, taken on the line II-II in Fig. I. Fig. III is a transverse sectional view of the charging vessel shown in longitudinal section in Fig. II. Fig. IV is a sectional view of the clamping adjustable bearing for said charging vessel, taken on the line IV-IV in Fig. II. Fig.

V is a side view of the upper portion of a gas-producer casing or retort provided with modified means for adjusting the charging vessel. Figs. VI and VII are sectional views showing modified forms of charging vessels. Fig. VIII is a side view of the upper portion of a gas-producer casing or retort, showing a modified embodiment of my invention. Fig. IX is a sectional view taken on the line IX-IX in Fig. VIII.

In said figures, 1 is the gas-producer casing or retort, whose mouth 2 is provided with the flange-seat 3. The bearing-housings 4 and 5 are mounted in alinement on opposite sides of said retort-mouth, as best shown in Fig. II, 55 and serve to support the hopper 6 in registry with the fuel-opening 7 in the charging vessel 8. The trunnions 9 and 10 of said vessel 8 are respectively mounted in slide-bearing boxes 11 and 12, and, as shown in Figs. I, II, 60 and IV, the trunnion 10 is provided with the lever-handle 14, by which said vessel 8 may be rocked in said bearings to deliver the fuel charge through the retort-mouth.

The bearing 11 is maintained in definite 75 but variable position with respect to the housing 4 by means of the adjusting-screw 16, which is in threaded engagement with the aperture 17 in said housing and provided with the jam-nut 18.

The bearing 12 is provided with the adjusting-screw 20, which is entered in threaded engagement with the opening 21 in the strap 23 and provided with the jam-nut 24. As shown in Figs. II and IV, the strap 23 is mounted 80 upon the eccentric portion 26 of the shaft 27, whose opposite concentric ends are mounted in the bearing-lugs 29 30 of the housing 5. Said shaft is provided with the operating-lever 31, by which it may be oscillated to raise 85 or lower the strap 23, so as to release the slide-bearing 12 or press it and the vessel 8 downwardly to seal the mouth of the retort, it being understood that said vessel 8 is capable of gyrating slightly with the bearing 11 90 upon the point of the adjusting-screw 16.

Other means than those above described may be employed to vary the pressure of the charging vessel upon its seat in the mouth of the retort. For instance, in Fig. V the trun- 100

nion 35 of the charging vessel 36 is mounted in the slide-bearing 38, which may be pressed down or released by the adjusting-screw 39, which is in threaded engagement with the housing 40 and provided with the handle 41—that is to say, the adjusting-screw 39 and its handle 41 can effect the same variation in pressure on the vessel as the adjusting-screw 20, strap 23, eccentric 26, and lever 31, above 10 described.

As indicated in Figs. II and III, the interior of the charging vessel may be provided with the diaphragm or rib 9. Said diaphragm or rib stiffens the vessel between its supporting trunnions and thus prevents distortion of the vessel-walls and consequent leakage between said walls and the seat when the clamping pressure is applied to the trunnions and insures that the fuel shall rotate with the vessel, 15 thus aiding in preventing it spilling, and also facilitates the discharge of the fuel when the vessel is in proper position therefor.

In Figs. I to V, inclusive, the charging vessel is spherical in form, and therefore adapted 20 to fit a circular seat in the retort. However, it is to be understood that any form of vessel may be employed which has a surface of revolution of such extent that a seat can be made which will fit the vessel closely both in the 25 position for receiving the fuel charge and in the position for emptying the same into the retort. For instance, Fig. VI shows the vessel 43 so shaped as to fit the seat-flange 44, surrounding the mouth 45, which is of irregular 30 contour. Fig. VII shows the vessel 46 of such configuration as to fit the seat-flange 48 around the mouth 49, which is of double hyperbolic contour, and Figs. VIII and IX show a cylindrical vessel with a cylindric seat.

Referring to the form of my invention shown 35 in Figs. VIII and IX, the producer casing or retort 50 is provided with a flange-seat 52 at its mouth 53, and the bearing-housings 54 and 55, alined on opposite sides thereof, support 40 the hopper 56 in registry with the fuel-opening 57 in the cylindrical charging vessel 58. The trunnions 59 and 60 of said vessel 58 are 45 respectively mounted in slide-bearing boxes 61 and 62, provided with springs 63 and 66, 50 which tend to press the vessel 58 upon its seat and seal said retort 50. The trunnion 60 is conveniently provided with the lever-handle 68, by which the vessel 58 may be rocked upon 55 said seat 52.

It may be noted that the various forms of 60 fuel-charging vessels above described are similar in that their perimeters are symmetrical with respect to their axes of rotation, so as to present equal cross-sectional areas within the retort-mouths in different rotary positions of 65 said vessels, and that said vessels are each arranged to hermetically seal its retort in both the position for receiving the fuel charge and in the position for emptying the same into the retort, so as to prevent the passage of air or

gas through the retort-mouth. It must also be noted that my improvements are advantageous over the single or double bell-valve, as well as the large gas-valves and other similar arrangements now in use as gas-retort 70 chargers, because in all of these devices the dirt and dust of the fuel are placed in actual contact with the finished surfaces of the valves and their seats, thus preventing a clean and gas-tight joint, whereas in my improvements 75 none of the fuel or its dirt comes in contact with the finished surfaces either of vessel or seat and the rocking of the vessel upon its seat tends continually to wear the seat to a 80 tighter fit.

Although I prefer to provide the charging vessel with distinct means to adjustably press it upon its seat at the retort-mouth, as above described, it may be noted that an air-tight 85 joint may be maintained between the retort-mouth and the vessel by the mere weight of the latter. Moreover, it is obvious that various modifications may be made in the details of construction and arrangement of my invention without departing from its essential 90 features.

I claim—

1. In a gas-retort charger, the combination with a retort having a mouth surrounded by a seat; of a charging vessel constructed to oscillate to deliver fuel to the retort; and, means arranged to vary the pressure upon said vessel to alternately seal the retort-mouth and permit the movement of said vessel, substantially as set forth. 95

2. In a gas-retort charger, the combination with a retort having a mouth surrounded by a seat; of a charging vessel constructed to oscillate to deliver fuel to the retort; and, adjustable means to vary the pressure of said vessel upon said seat, to alternately seal the retort-mouth and permit movement of said vessel, substantially as set forth. 105

3. In a gas-retort charger, the combination with a retort having a mouth surrounded by a seat; of a charging vessel constructed to oscillate to deliver fuel to the retort; and, means to vary the pressure of said vessel upon the retort-mouth, comprising an adjustable screw, substantially as set forth. 110

4. In a gas-retort charger, the combination with a retort having a mouth surrounded by a seat; of a charging vessel, arranged to deliver the fuel charge to the retort; and, means to press said vessel to seal the retort-mouth; comprising an eccentric in operative relation with a trunnion on said vessel, substantially as set forth. 120

5. In a gas-retort charger, the combination with a retort having a mouth surrounded by a seat; of a charging vessel arranged to be oscillated upon trunnions alined upon opposite sides thereof; slide-bearing boxes for the respective trunnions; housings mounted upon the retort to receive said boxes; means con- 125 130

necting one of said housings with its respective box, arranged to maintain said box in adjusted position; a shaft mounted to oscillate in the other of said housings; an eccentric upon said shaft; and, means connecting said eccentric with the other of said boxes, whereby said vessel may be clamped upon said seat, substantially as set forth.

6. In a gas-retort charger, the combination with a retort having a mouth surrounded by a seat; of a charging vessel arranged to be oscillated upon trunnions alined upon opposite sides thereof; slide-bearing boxes for the respective trunnions; housings mounted upon the retort to receive said boxes; a set-screw entered in one of said housings, arranged to maintain one of said boxes in adjusted position; a shaft mounted to oscillate in the other of said housings; an eccentric upon said shaft; a strap for said eccentric; a set-screw carried by said strap in adjustable connection with the other of said boxes; and, means to oscillate said shaft, whereby said vessel may be clamped upon said seat, substantially as set forth.

7. In a gas-retort charger, the combination with a retort having a mouth surrounded by a seat; of a charging vessel provided with a fuel-opening, and arranged to be oscillated upon trunnions alined upon opposite sides thereof; slide-bearing boxes for the respective trunnions; housings upon the retort to receive said boxes; a hopper supported by said housings, arranged to register with said vessel opening; a set-screw entered in one of said housings, arranged to maintain one of said boxes in adjusted position; a shaft mounted to oscillate in the other of said housings; an eccentric upon said shaft; a strap for said eccentric; a set-screw carried by said strap in adjustable connection with the other of said

boxes; and, means to oscillate said shaft, whereby said vessel may be clamped upon said seat, substantially as set forth.

8. In a gas-retort charger, the combination with a retort having a mouth surrounded by a seat; of a charging vessel entered in the mouth of said retort and provided with trunnions alined upon its opposite sides; a gyratory support for one of said trunnions; a support for the other of said trunnions arranged to permit it to oscillate; and means to shift said second support to clamp the vessel upon said seat, substantially as set forth.

9. In a gas-retort charger, the combination with a charging vessel arranged to be oscillated upon trunnions alined upon its opposite sides; of a fulcrum for one of said trunnions; and, means operatively connecting with the other of said trunnions, to clamp said vessel toward the retort to seal the mouth of the latter, substantially as set forth.

10. In a gas-retort charger, the combination with a retort having a mouth provided with a seat; of a charging vessel constructed to oscillate and arranged to form a tight joint on said seat both in the position for receiving the fuel charge and in the position for emptying the same into the retort, substantially as set forth.

11. In a gas-retort charger, the combination with a retort having a mouth surrounded by a seat; of a charging vessel entered in the mouth of said retort and provided with trunnions on its opposite sides, and having an internal stiffening web or rib, substantially as set forth.

In testimony whereof I have hereunto signed my name, at Philadelphia, Pennsylvania, this 9th day of January, 1904.
